UNITED STATES PATENT OFFICE.

HENRY M. LOOMER, OF BEVERLY, MASSACHUSETTS.

THREADING-DIE AND HOLDER.

1,212,970.

Specification of Letters Patent. Patented Jan. 16, 1917.

Application filed November 6, 1911. Serial No. 658,871.

To all whom it may concern:

Be it known that I, HENRY M. LOOMER, a citizen of the United States, residing at Beverly, in the county of Essex and State 5 of Massachusetts, have invented certain Improvements in Threading-Dies and Holders, of which the following description, in connection with the accompanying drawings, is a specification, like reference characters 10 on the drawings indicating like parts in the several figures.

This invention relates to improvements in threading dies and holders therefor.

An object of this invention is to produce a 15 grindable button die and thereby extend the term of usefulness of such dies.

Another object of this invention is the provision of such means for adjusting the cutting edges of such dies that in any adjustment thereof into the work diametrically opposite teeth will penetrate equally and thus afford a more accurate lead. Heretofore the means often used for this 25 purpose would force two circumferentially adjacent sets of teeth into greater penetration into the work than the other sets of teeth of the die.

This invention further contemplates an improvement in the construction and mode 30 of operation of threading dies.

Referring to the drawings, Figure 1 is an assembly view, partly in section, of what is known as a button die and holder, provided with improved means for adjusting 35 the penetration of the die into the work; Fig. 2 shows the button die and the improved means for adjustment of penetration in their relative positions in the holder.

In Fig. 1, the shank or spindle 1 of the 40 die holder may be of any suitable size or shape for use in a screw machine, lathe, hand stock, or such other desirable operating means as may be used for threading dies. This spindle 1 is shown provided 45 with a wedge separating bar 3 which is operated by an adjusting cone point set-screw 5. In order that the inclined faces 9 of the separating bar 3 shall be presented in proper coincidence with inclined faces 11 of the 50 button die, a slotted disk 2 is provided which engages a slotted surface 6 of the separating bar 3 so as to prevent rotation of the bar 3 in the spindle head 4. This disk is held in place by screw 8.

55 In Fig. 2 particularly the relation of the separating bar 3 and the button die 10 is

shown. It will be seen from these views that adjustment of the set screw 5 will elevate or depress separating bar 3. Elevation of bar 3 tends by means of the coincident inclination of its faces 9 with the inclined faces 11 to separate the sections 13 of the die and thus diminish the penetration of all the cutting points 15 into the work. It will be seen that by the provision 60 of two oppositely disposed separating bars, the equal elevation of these bars will adjust the two sections 13 of the die in symmetrical relation to a plane passing through the center of the holder and midway between the 65 sections so as to equally decrease the amount of penetration into the work of such cutting points 15 as are diametrically opposite each other. After suitable elevation or depression of the separating bars 3 to adjust desirably 70 the amount of penetration of the die into the work the cap 7 is placed on the threaded end 17 and upon its being screwed onto the holder the surface 19 will bring the button die into proper perpendicular relation to 75 the axis of the holder. The cap 7 is provided with a knurled portion 21 to enable the operator to obtain a better "grip" upon it. In order to increase the amount of penetration of the cutting points 15 it is 80 simply necessary to relieve the pressure of surface 19 upon the die by unscrewing the cap 7 and adjust the set screws 5 outwardly, thus allowing the separating bars 3 to descend and upon tightening the cap 7 the 85 button die will be drawn down upon the spindle head. In this downward motion of the die the conical recess 23 tends to close the sections 13 of the die and thus increases the amount of penetration of the cutting 90 points 15 into the work. It should be noticed that in the construction here shown the cone point set screws 5 which operate the separating bars 3 are always accessible and the die 10 may be quickly adjusted 95 without entirely removing the cap 7. It should also be noticed that the upper and lower portions of the die sections 13 have similar conical surfaces so that the die may be reversed in the holder to cut close to 100 shoulders in the work. A wire 12 seated in the groove 14 keeps the die sections 13 together and prevents the loss of either section when the die is removed from the 105 holder. Owing to the spring temper of the 110 wire 12, it may be easily removed from the sections 13 so that said sections may be

separated when it is desired to sharpen the die. This operation of sharpening is very simple because, when the sections are taken apart, the cutting edges all lie in planes which are unobstructed except in one direction and there is sufficient unobstructed space adjacent to this plane to allow a grinding wheel or other sharpening implement to be operated therein.

10 Having described my invention, what I claim as new and desire to secure by Letters Patent is:—

1. A button threading die and holder having, in combination, a shank, a wedge-shaped member for spreading the die, adjusting means for said wedge-shaped member, means for maintaining said wedge-shaped member in proper alignment, a head on said shank, conically recessed, oppositely disposed surfaces on said die which are capable of alternately registering with said recessed head, a retaining cap for maintaining said die against said head and a yielding member to connect the members of said die when removed from said head.

2. A button die and holder having, in combination adjustable members mounted in and supported by the holder and constructed and arranged to vary the depth of cut of the die, each of said members being provided with two angularly disposed plane surfaces for engagement with corresponding faces on the die.

3. A button die and holder having, in combination, wedge-shaped members and screws for adjusting said members, said screws being located externally to the die and at an angle to the wedge-shaped members, all so constructed and arranged that the penetration of the cutting points into the work may be proportionally adjusted by means external to the die and located at an angle to its axis.

4. A button threading die, a die holder and a cap so constructed and arranged with relation to each other that the die is automatically centered by co-acting cone faces on the die and holder and is brought into a plane at right angles to the axis of the holder by co-acting flat faces on the die and cap.

5. The combination of a threading die formed in sections having thread cutting portions, a holder for said die, a cap for said holder, separating wedges carried by the holder for spreading the sections of the die apart, adjusting means for adjusting said separating wedges, said holder and cap tending to force the thread cutting portions of said die sections to penetrate into the work

and said separating wedges serving as a stop for the penetration of said thread cutting die sections.

6. The combination of thread cutting die sections, a holder therefor, a cap for said holder, said sections, holder and cap being so constructed and arranged that the holder and cap coöperate to force the die sections together and to increase their penetration into the work, separating wedges contained in said holder for determining the amount of penetration of the die sections into the work, and adjusting means for said separating wedges, said adjusting means being in said holder and operable from without said holder without removing said cap from the holder.

7. A sectional button threading die and holder therefor having, in combination, a plurality of wedge-shaped members constructed and arranged to slide in an axial direction, without turning, to separate the sections of the die and to prevent relative rotation between the die and holder.

8. A sectional button threading die and holder therefor having, in combination, a plurality of adjustable wedge-shaped members constructed and arranged to slide in an axial direction, without turning, to vary the size of the die and to rotate the die relatively to the work, substantially as described.

9. A sectional button threading die, a holder therefor, a cap for said die and holder, a plurality of wedge-shaped die separating members contained in said holder, said members co-acting with inclined, plane surfaces upon the sections of the die, and means for preventing said separating members from turning and for retaining them in the holder.

10. As a new article of manufacture, a button threading die composed of a plurality of sections, the dividing surfaces between sections consisting of inclined, plane surfaces.

11. For an adjustable button threading die made in sections, a holder, and adjustable separating members having ends with angularly disposed plane surfaces, said members being contained in the holder and said ends being constructed and arranged to project from the holder into the spaces between the sections of the die.

In testimony whereof I have signed my name to this specification in the presence of two subscribing witnesses.

HENRY M. LOOMER.
